[57] CLAIM

The ornamental design for a combined mail delivery indicator and holder therefor, as shown and described.

DESCRIPTION

FIG. 1 is a perspective view of a combined mail deliver indicator and holder therefor showing my new design; the broken away chain has been drawn to shown varying lengths;

FIG. 2 is a perspective view showing the indicator resting in the holder;

FIG. 3 is a front elevational view thereof;

FIG. 4 is a rear elevational view thereof;

FIG. 5 is an end elevational view as seen from the left end of FIG. 2;

FIG. 6 is an end elevational view as seen from the right end thereof;

FIG. 7 is a top plan view thereof;

FIG. 8 is a bottom view thereof; and,

FIG. 9 is a perspective view thereof; the broken lines of the mailbox are for environmental purposes only.

FIG. 1

FIG. 2
